(57) **CLAIM**

The ornamental design for a packaging pouch as shown and described.

DESCRIPTION

The file of this patent contains at least one drawing/photograph executed in color. Copies of this patent with color drawing(s)/photograph(s) will be provided by the Office upon request and payment of the necessary fee.

1. Packaging pouch

2. Packaging pouch

1.1 : Front

1.2 : Back

1.3 : Left

1.4 : Right

1.5 : Top

1.6 : Bottom

1.7 : Perspective

2.1 : Front

2.2 : Back

2.3 : Left

2.4 : Right

2.5 : Top

2.6 : Bottom

2.7 : Perspective

The broken lines in the drawings represent features of the packaging pouch that form no part of the claimed design; the dash-dot broken lines in the drawings represent a border separating areas that form no part of the claimed design; design 2 is a colour embodiment of the same design as claimed in figs. 1.1 to 1.7.

1 Claim, 14 Drawing Sheets
(5 of 14 Drawing Sheet(s) Filed in Color)
